(57) **CLAIM**

The ornamental design for a pry bar head as shown and described.

DESCRIPTION

FIG. 1 is a perspective view of a pry bar head showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof showing the pry bar in use.

The broken lines in FIG. 8 depicting a pry bar illustrate environment. All other broken lines depict portions of the pry bar head. None of the broken lines form any part of the claimed design.

1 Claim, 8 Drawing Sheets
